UNITED STATES PATENT OFFICE

EMIL J. NARGI, SR., OF PASSAIC, NEW JERSEY

DESIGN FOR A POWDER PUFF

Application filed April 25, 1931. Serial No. 39,625. Term of patent 3½ years.

To all whom it may concern:

Be it known that I, EMIL J. NARGI, SR., a citizen of the United States, residing at 197 Autumn Street, Passaic, in the county of Passaic and State of New Jersey, have invented a new, original, and ornamental Design for a Powder Puff, of which the following is a specification, reference being had to the accompanying drawings, forming a part thereof, and showing in Fig. 1 a front view of a powder puff embodying my new design, and in Fig. 2 a plan view thereof.

I claim:

The ornamental design for a powder puff substantially as shown.

EMIL J. NARGI, SR.
